BUILDING WALL CONSTRUCTION AND METHOD OF MAKING THE SAME

Filed July 21, 1926

UNITED STATES PATENT OFFICE.

FRANK NILES AND LESTER NILES, OF SANTA BARBARA, CALIFORNIA.

BUILDING-WALL CONSTRUCTION AND METHOD OF MAKING THE SAME.

Application filed July 21, 1926. Serial No. 123,940.

This invention relates to improvements in building walls and to a method for constructing the same.

An object of this invention is to provide an improved building wall which has a metallic reinforcement, wherein the reinforcement has applied thereto a self-hardening plastic material in such a manner that the reinforcement will be arranged at the center of the plastic material to properly reinforce it. By the improved construction a wall is provided which is extremely strong and which for all practical purposes may be considered as earthquake-proof.

Another object of this invention is to provide a novel method for constructing building walls of the improved construction, enabling the wall to be very easily and quickly formed, requiring a minimum amount of time, labor and expense.

With the foregoing and other objects in view which will be made manifest in the following detailed description and specifically pointed out in the appended claims, reference is had to the accompanying drawings for an illustrative embodiment of the invention, wherein:

Figure 1 is a perspective view of a portion of the improved building wall during the initial steps of construction,

Fig. 2 is a vertical section illustrating the wall as being partially constructed,

Fig. 3 is a vertical section illustrating a portion of Fig. 2 on an enlarged scale,

Fig. 4 is a vertical section illustrating the finished building wall, and

Fig. 5 is a vertical section illustrating a portion of Fig. 4 upon an enlarged scale.

Referring to the accompanying drawings wherein similar reference characters designate similar parts throughout, in constructing the improved wall a plurality of vertical studs 10 are first erected. These studs are preferably formed of metal and in the present instance they are shown as being formed of channel iron. Cross bars 11 are arranged horizontally across the studs 10, and in the drawing these cross bars are also formed of channel iron, being much smaller than the channel irons forming the studs 10. They are fastened to the studs as by tie wires 12. Against the cross bars there is secured a layer 13 of relatively fine metal fabric. This metal fabric may be of various materials, such as for example, a rela-

tively fine woven wire, expanded metal, metal laths or any equivalent substance, having the general characteristic that its interstices be fairly small. This layer of metal fabric is fastened to the cross bars 11 by means of tie wires 14. Against the metal fabric layer 13 there is fastened a relatively heavy metal reinforcement, illustrated upon the drawing as being relatively heavy wires or rods 15 which are woven together to form a heavy screen. The purpose of the heavy reinforcement is to form the major reinforcement for the wall. This reinforcement may be fastened in place by means of the tie wires 14.

After the above mentioned construction is completed, a layer of self-hardening plastic material 16 is applied. This self-hardening material may be plaster or any equivalent composition, and it is applied to the back or inside of the metal fabric 13. On applying this layer of self-hardening plastic material, it is worked sufficiently to force portions of it through the interstices in the metal fabric layer 13. These portions which are forced through the metal fabric layer are indicated at 16' upon Fig. 3. As soon as this layer of self-hardening plastic material has set, another layer of self-hardening plastic material indicated at 17 is applied to the front or the outside of the metal fabric layer 13. This layer 17 adheres to the layer 16 and imbeds the reinforcement 15 therein. In this way by applying the self-hardening plastic material to both sides of the metal fabric, the metal fabric and reinforcement will be caused to assume a position at substantially the center of the plastic material so that it will properly reinforce the plastic material.

While the metal fabric offers a small degree of reinforcement, this material is not intended to greatly reinforce the wall. The major reinforcement is provided by the heavy reinforcing material, which is primarily designed for this purpose. The primary purpose of the metal fabric is to support the back layer of self-hardening plastic material, and to enable a bond to be formed between the two layers 16 and 17 to enclose and imbed the reinforcement 15 therein. For this reason the metal fabric may be of a rather weak bendable material for its primary purpose is merely to support the plastic material until the plastic material has

2
hardened and set, enclosing the reinforcement 15.

The above described construction is quite an improvement and is distinguishable from constructions where the plastic material is applied merely to the forward side of the metal fabric layer and worked through it. In such prior constructions the portions of the plastic material which work through the metal laths do not form a uniform solid layer of plastic material on the back of the metal fabric. Consequently, the portions of the plastic material on the back of the metal fabric are weak so that the wall constructed has the reinforcement only at the back of the solid plastic material. Unless the reinforcement is at the center, it will not properly reinforce the self-hardened plastic material. The layer 17 may serve as a scratch 20 coat for the wall or may present the finished surface on the outside of the wall. In the event that the layer 17 provides merely a scratch coat, a finish coat 18 can be applied. In this way the outer side of the building wall is constructed.

The inner side of the building wall can be constructed in the usual manner after the outside has been completed. This is illustrated in Fig. 4 as consisting of laths 19 over which inside plaster 20 is applied. It will of course be understood that any other construction on the inside can be employed, such as for example metal laths and plaster or the like.

From the above described construction and method of making the same, it will be appreciated that a novel construction and method is provided, utilizing back plastering, that is, applying plaster or equivalent material to the back as well as the front of the metal fabric layer 13 to cause the metal fabric layer and the reinforcement 15 to assume a position at the center of the plastic material to properly reinforce it and form a rigid, strong and earthquake-proof wall.

It will be understood that various changes may be made in the detail of construction without departing from the spirit and scope of the invention as defined by the appended claims.

We claim:

1. A wall including studs, a layer of relatively fine metal fabric fastened to the studs, reinforcing means positioned against said layer, a layer of self-hardening plastic material applied to the back of said layer and worked therethrough, and a second layer of self-hardening plastic material applied to the front of the layer imbedding the reinforcing means therein.

2. A wall including studs, a layer of relatively fine metal fabric fastened to the studs, reinforcing means positioned against said layer, a layer of self-hardening plastic material applied to the back of said layer and

worked therethrough, a second layer of self-hardening plastic material applied to the front of the layer imbedding the reinforcing means therein, and a finish coat applied to said second layer. 70

3. A wall including studs, a layer of relatively fine metal fabric fastened to the studs, and a self-hardening plastic material applied to said layer and extending therethrough, said plastic material being of approximately equal thickness upon both sides of said metal fabric, whereby the metal fabric will be positioned substantially at the center of the plastic material, affording some degree of reinforcement. 75 80

4. A wall including studs, a layer of relatively fine metal fabric fastened to the studs, and a self-hardening plastic material applied to said layer and extending therethrough, said plastic material being of approximately equal thickness upon both sides of said metal fabric, whereby the metal fabric will be positioned substantially at the center of the plastic material, affording some degree of reinforcement, both surfaces of the 85 90 plastic material being relatively smooth.

5. A building wall including studs, a layer of relatively fine metal fabric fastened to the studs, a relatively heavy metal reinforcement positioned against the outside of the fabric, a self-hardening plastic material applied to the back or inside of the metal fabric and extending therethrough, and a self-hardening plastic material applied to the front side of the fabric adhering to the first mentioned self-hardening material and imbedding the metal reinforcement therein, whereby the fabric and reinforcement will be arranged at substantially the center of the plastic material to properly reinforce it. 100 105

6. A building wall including studs, a layer of relatively fine metal fabric fastened to the studs, a relatively heavy metal reinforcement positioned against the outside of the fabric, a self-hardening plastic material applied to the back or inside of the metal fabric and extending therethrough, a self-hardening plastic material applied to the front side of the fabric adhering to the first mentioned self-hardening material and imbedding the metal reinforcement therein, whereby the fabric and reinforcement will be arranged at substantially the center of the plastic material to properly reinforce it, and a finish coat of plastic material applied to 110 115 the last mentioned plastic material.

7. The method of constructing building walls which consists of erecting studs, mounting a layer of relatively fine metal fabric against one side of the studs, mounting a layer of relatively heavy reinforcement against the metal fabric, applying a self-hardening plastic material to both sides of the metal fabric, imbedding the fabric and reinforcement therein whereby the fabric and 120 125 130 reinforcement therein.

reinforcement will be arranged at substantially the center of the plastic material to reinforce it.

8. The method of constructing building walls which consists of erecting studs, mounting a layer of relatively fine metal fabric against one side of the studs, mounting a layer of relatively heavy reinforcement against the metal fabric, applying a self-hardening plastic material to both sides of the metal fabric, imbedding the fabric and reinforcement therein whereby the fabric and reinforcement will be arranged at substantially the center of the plastic material to reinforce it, mounting laths against the other sides of the studs, and applying plaster thereto.

9. The method of constructing building walls which consists of erecting studs, mounting a layer of relatively fine metal fabric against one side of the studs, mounting a layer of relatively heavy reinforcement against the metal fabric, applying a self-hardening plastic material to both sides of the metal fabric, imbedding the fabric and reinforcement therein whereby the fabric and reinforcement will be arranged at substantially the center of the plastic material to reinforce it, and applying a finish coat to the outer side of the plastic material. 20 25 30

In testimony whereof we have signed our names to this specification.

FRANK NILES.
